UNITED STATES PATENT OFFICE.

ETHAN ROGERS, OF BALLSTON, NEW YORK.

DESIGN FOR A DIE-BLOCK.

SPECIFICATION forming part of Design No. 29,136, dated August 2, 1898.

Application filed July 11, 1898. Serial No. 685,708. Term of patent 14 years.

To all whom it may concern:

Be it known that I, ETHAN ROGERS, a citizen of the United States, residing at Ballston, county of Saratoga, State of New York, have 5 invented and produced a new and original Design for a Die-Block, of which the following is a specification, reference being had to the accompanying drawings, forming a part thereof.

Figure 1 of the drawings is a plan view of 10 the supporting-die, showing my new design. Fig. 2 is a vertical section taken on the broken line 2 2 in Fig. 1.

The leading feature of my design consists 15 of the vertically-extended ribs A, A', A², and A³, which severally project horizontally into the cavity B in the upper part of the die-block B'. The ribs are arranged in pairs,

each pair composed of two oppositely-disposed members. The members A and A', comprising one pair, are located near one end of 20 the die-cavity B, and the members A² and A³, comprising the other pair, are located near the other end of the die-cavity.

What I claim as new, and desire to secure by Letters Patent, is—

The design for a die-block herein shown and described.

In testimony whereof I have hereunto set my hand this 2d day of July, 1898.

ETHAN ROGERS.
